UNITED STATES PATENT OFFICE.

KARL P. McELROY, OF WASHINGTON, DISTRICT OF COLUMBIA, ASSIGNOR TO CHEMICAL DEVELOPMENT COMPANY, A CORPORATION OF MAINE.

ELECTROLYSIS OF CHLORIDS.

1,264,535.

Specification of Letters Patent. Patented Apr. 30, 1918.

Application filed December 9, 1915. Serial No. 65,983.

To all whom it may concern:

Be it known that I, KARL P. McELROY, a citizen of the United States, residing at Washington, in the District of Columbia, have invented certain new and useful Improvements in Electrolysis of Chlorids, of which the following is a specification.

This invention relates to the electrolysis of chlorids; and it comprises an improvement in the method of electrolyzing aqueous solutions of potassium chlorid and sodium chlorid for the manufacture of alkali and chlorin wherein the production of chlorin as such is obviated and in its lieu are obtained other and more valuable volatile products, such volatile products being removed in the vapor form from the zone of electrolysis as fast as formed for condensation elsewhere, the electrolytic liquid being maintained hot and gases or vapors composed of or comprising unsaturated hydrocarbons being introduced into the electrolytic cell in the vicinity of the anode while vapors of products formed by reaction are removed from the cell and condensed by suitable means; and, more specifically, it comprises a method of producing chlorhydrins wherein an aqueous chlorid solution is electrolyzed at or about the boiling point of water under the pressure prevailing and during the electrolysis a gas or vapor composed of or comprising an olefin or mixture of olefins is introduced into the electrolytic apparatus in the vicinity of the anode and the vapors of volatile products formed by reaction of such gas or vapor with the chlorin evolved at the anode are removed and condensed; and it further comprises as a new organization of apparatus elements an electrolytic cell adapted for the electrolysis of aqueous chlorid solutions, means for heating the same, means for introducing hydrocarbon gases or vapors in proximity to the anode and means for removing and condensing vapors of volatile products; all as more fully hereinafter set forth and as claimed.

In the manufacture of alkali by the electrolysis of solutions of potassium chlorid and sodium chlorid, corresponding amounts of free chlorin are necessarily produced while the market demand for chlorin is not as great as that for alkali. It is one of the objects of the present invention to improve the alkali-making process by the substitution of the production of other and more

valuable products for that of chlorin. To this end, in the electrolytic operation the chlorin evolved at the anode is caused to react within the cell with unsaturated hydrocarbons to produce various volatile bodies of value for solvent and other purposes, the reaction being carried on at such a temperature that the new products are maintained in vapor form while the vapors are removed from the zone of reaction as fast as formed.

Olefin hydrocarbons, of the general formula C_nH_{2n} , such as ethylene, C_2H_4 , and its homologs, react with chlorin by simple addition, forming olefin chlorids, $C_nH_{2n}Cl_2$. In the case of ethylene, $C_2H_4Cl_2$, ethylene chlorid or "Dutch liquid," is produced. These olefin chlorids are volatile liquids insoluble in water and of value for solvent purposes though not now made commercially.

As I have discovered, and have elsewhere described and claimed, the action of chlorin upon the unsaturated gaseous hydrocarbons, such as the olefins, is however, not necessarily one of simple addition. Ethylene, for example, in contact with chlorin under certain conditions does not form "Dutch liquid" by simple addition but may instead form ethylene chlorhydrin, C_2H_4OHCl ; a body which is nearly related to ordinary ethyl alcohol C_2H_5OH ; differing from it by containing an atom of chlorin in lieu of one of hydrogen. The other olefins, propylene, the butylenes, the amylenes, etc., form chlorhydrins in a similar way. These chlorhydrins are all bodies more or less soluble in water, of fragrant alcoholic odor and of excellent solvent properties for varnish making, celluloid manufacture, etc. The chlorhydrins of the lower or gaseous olefins, ethylene, propylene and the butylenes as well as of the amylenes all have nearly the same boiling points.

A necessary condition for the formation of chlorhydrins from the olefins and chlorin is the presence of water in relatively large amount, either as liquid water or as steam. Under these conditions, half the chlorin reacts with part of the hydrogen of the water to form hydrochloric acid while the remaining chlorin and the remaining O and H of the water or steam unite with the olefin forming a chlorhydrin. If the reaction be performed in the presence of steam, at 97-100° C. the chlorhydrin is formed and

remains in the vapor state. While the olefin chlorhydrins are relatively high boiling bodies, they form a low boiling mixture with water vapor. In another application 34678, filed June 17, 1915, I have described and claimed a method of forming chlorhydrins based upon these facts, chlorin and gaseous olefin being caused to contact together in an atmosphere of steam at a temperature around 100° C. Under these circumstances olefin chlorhydrins are formed and pass out of the apparatus as vapor to be subsequently condensed. Half the chlorin is converted into hydrochloric acid which condenses and remains in the apparatus and which may be drawn off as an aqueous solution. The process is there described and claimed as being particularly suitable for treatment of the mixture of olefins which is contained, to the extent of 40 to 60 per cent., in oil gas made from petroleum oils at relatively low temperatures.

In the present invention in lieu of separately preparing chlorin and then admixing it with the olefinic gases, I directly introduce the gases into the electrolytic cell, forming the chlorhydrins in the cell and withdrawing them therefrom as vapors which are subsequently condensed.

To this end I perform the electrolysis of a solution of salt (NaCl) or of any other suitable chlorid in any suitable form of cell now used to manufacture chlorin and alkali; but I maintain the temperature of the cell considerably higher than is usually the case. This is for a number of reasons. One is that I wish to maintain an atmosphere of steam within the cell and another is that I wish to produce and maintain the chlorhydrins in vapor state until they can be removed from the cell; and therefore do not wish them to condense in the electrolyte.

While the present process is applicable to the treatment of pure olefins such as ethylene, propylene, the butylenes, the amylenes, the hexylenes, etc., I shall hereinafter speak more specifically of the treatment of oil gas, it being understood that such gas is merely typical of gases containing olefins and of the gaseous olefins themselves, or of vaporized low boiling olefins such as are contained in unsaturated gasoline.

Oil gas when properly made is a mixture of saturated and unsaturated hydrocarbons. The saturated hydrocarbons, methane, ethane, propane, etc., are inert in the present process. A little hydrogen may be present but this is also here inert. There should not be much in well made gas. The unsaturated gases present are mainly olefins, the proportion of acetylenes and diolefins being very small in gas made from petroleum oils around 700° C. Ethylene and propylene are the predominant olefins but butylenes and amylenes are usually present in some amount. If it be de-

sired to remove the butylenes, amylenes, etc., leaving the ethylene and propylene, the gas may be compressed and chilled to condense out liquefiable gases and vapors; or it may be washed with chilled oil. Or it may be both pressed and chilled and scrubbed with chilled oil. However, for most purposes the presence of the amylenes and the butylenes does no harm. Chlorhydrins of ethylene, and propylene, and of the amylenes and butylenes all boil within a narrow range, between 127° and 135° C.; so that a mixture of such chlorhydrins such as is obtained on directly treating unpurified oil gas by the present process is, for most purposes, a unitary body in the sense that it does not have constituents which can be readily separated by fractional distillation. For many solvent purposes this mixture is more desirable than the several pure bodies composing it. The boiling point of a mixture of chlorhydrins obtained from crude oil gas ranges, in the dry state, as stated, between 127° and 135° C. In the presence of sufficient water the mixture will boil between 97-99° C.

On passing the oil gas over or through a hot electrode evolving chlorin and at a temperature between 97-100° C. the chlorin and the olefins react quietly to form vapors of chlorhydrins. These vapors may be led off from the cell and condensed in any suitable way. If the amount of steam accompanying them is large the vapors condense as a clear water solution of chlorhydrins; if it be small in amount, or if a reflux condenser be adopted, the distillate condenses as a mixture of oily chlorhydrins containing some water and water carrying dissolved chlorhydrins. This mixture may be settled and the oil and water separated. The water solution on redistillation in a column still gives oily chlorhydrins and saturated solution. The aqueous solution formed on condensing the effluent vapors from a cell where much steam goes forward, may be similarly distilled to recover the chlorhydrins in the oily form. The oily chlorhydrins may be dehydrated by distillation or by treatment with salt followed by distillation. In dry form, without separation of the individual components the condensed chlorhydrin mixture forms an excellent solvent capable of dissolving cellulose acetate and many other coating materials and capable of replacing amyl acetate and other expensive solvents for many uses.

Under the stated conditions, the hydrochloric acid formed in the action is condensed, dissolves in the cell electrolyte and is reelectrolyzed to furnish more chlorin.

If the temperature of the vapors above the electrolyte be over 100° C. as may be the case in supplying live steam to such space, or is very much under 100° C. there is usually some formation of olefin chlorids. Superheated steam, that is steam over 100° C. at

atmospheric pressure does not have as much of the tendency favoring the production of chlorhydrins as steam at 100° C. while at temperatures much below 100° C. there is often not enough water vapor in the reaction space. Where olefin chlorids are produced, they separate from the aqueous condensate, being wholly insoluble in water. They however as a rule carry more or less chlorhydrins. 10 Where olefin chlorids and chlorhydrins are both produced in the cell, the separation formed is a turbid whitish looking material, sometimes floating on the water and composed of mutually dissolved chlorids, chlorhydrins and water. These whitish oil separations on washing with water give clear olefin chlorids, the chlorhydrins going into solution with the water. Washing with water may be used for the purpose of separating. 20

Any of the ordinary types of cell may be employed for the present purposes if it be provided with means for heating to 97°-100° C., with means for introducing gas and steam and means for removing and condensing vapor. In vertical types of diaphragm cells all the gas, advantageously in admixture with steam, may be bubbled up through the electrolyte near the anodes; in bell jar or 30 horizontal diaphragm types, it may be blown along the surface of the electrolyte in the anode chamber.

While chlorhydrin may be formed in chlorin evolving cells at a lower temperature; a temperature such that they do not volatilize to any material extent but remain in the electrolyte or separate from it physically as oils, this matter I do not herein claim, it forming part of the subject matter of my copending application 35505, filed June 22, 1915; the present invention relating more specifically to a process wherein the chlorhydrins are formed in the cell in the vapor state and are removed as such. 40

45 In the accompanying illustration I have shown more or less diagrammatically certain cheap, simple and effective types of cell. In this showing,

Figure 1 is a central vertical section of a 50 horizontal type of diaphragm cell;

Fig. 2 is a central vertical section, certain accessory parts being in elevation, of a type having a vertical diaphragm;

Fig. 3 is a vertical cross-section of a compact type of cell, having a plurality of units adapted for use in series; and

Fig. 4 is a fragmentary central longitudinal vertical section of two such units; and

Fig. 5 is a central longitudinal vertical 60 section of still another form of cell.

In the showing of Fig. 1 element 1 is an alkali chamber which may be made of concrete or any other suitable non-conducting material. At its base it is provided with 65 valved alkali outlet 2. At a high point it is

provided with hydrogen escape 3. At a lower point it is provided with steam inlet 4. Within this chamber is hung the cell proper. The side walls of the chamber inclosing the cell are spaced somewhat away to give a steam 70 space 5 therebetween. The walls carry a narrow iron plate 6 on which rest angle irons 7 extending the full length of the cell and serving to support it. The cell proper may be built of a frame of expanded metal or wire 75 netting 8 bent into the proper form. Within this netting is placed a lining 9 of tile or other acid resistant material. Ordinary slate does very well. The metal framework and slate lining being in position the 80 sides of the cell are plastered with a thin layer of concrete 10 extending nearly to the top of the slate lining and to its base and rigid with the stated angle irons. This layer grips the lining and makes the structure 85 unitary. The expanded metal or wire netting may extend across the bottom of the cell to form cathode 11. This cathode may be of copper, iron, or any other metal and may, as stated be the same piece of netting 90 that forms the side walls of the cell or it may be another piece laced to the side walls. Extending longitudinally along this cathode bottom is supply pipe 12 which may be of iron or other metal and may serve as a current lead to the cathode. It carries short glass or earthenware nipples 13 extending upwardly beyond a diaphragm layer 14. This diaphragm may be of asbestos having its pores filled with mineral matter such as 100 barium sulfate, talc, etc. Or asbestos fabric may be simply soaked in solution of silicate of soda and placed in position. On contact with strong salt solution this silicate of soda solution is salted out, forming a gelatinous 105 mass which fills the pores very effectually. Diaphragms of other material, such as porous concrete, may be employed. Above this diaphragm I have shown a second diaphragm 15 which may be of concrete or asbestos. 110 For this second diaphragm, asbestos treated with water glass or silicate of soda solution is useful. The second or false diaphragm serves to form a brine space between it and the lowermost diaphragm. Immediately above the false diaphragm are horizontal anodes 16 which may be of carbon or graphite. Above these anodes I may suspend a secondary cathode 17 for a purpose hereinafter set forth. At the top the cell 115 may be closed by slabs 18 of soapstone or slate. They may be notched at 19 to receive the upper extremities of the slate slabs forming the lining. The cell may be provided with steam inlets 20 and with vapor outlets 21 leading to any suitable condenser, (not shown). Gas may enter at special inlet 22 or be mingled with the steam by means of inlet 23. Inlet 90 may supply chlorin from any other source mixed with steam from 91. 130

In the use of the above described structure the cell is filled with brine through 12 to a point above the anodes 16. It is best to use a saturated brine. Weak brines may be 5 used but there is no advantage in this. Steam is now led into the interior of the cell through 20 and into the chamber below and around the cell through 4 until the liquid assumes a temperature of 97°-100° C. as 10 shown by thermometer 25. Thermometer 26 indicates the temperature of the vapor space. Gas is now led in through inlet 22 or 23 and mixes with the steam passing in at 20. The mixture of steam and gas passes 15 forward over the surface of the hot liquid and meets the chlorin which escapes from the electrolyte in admixture with more or less water vapor. Under these conditions the stated reaction takes place with formation 20 of chlorhydrin vapors and HCl. The temperature of the vapors being 97° or higher the chlorhydrin vapors do not condense; but the hydrochloric acid for the most part condenses and returns to the 25 electrolyte, where it is electrolyzed to reform chlorin. The false diaphragm 15 serves to prevent undue dilution of the dense brine layer between the electrodes.

Operation may be continued in this manner and as long as the cell is operating regularly the vapors escaping at 21 when condensed will be a clear liquid aqueous solution of chlorhydrins containing some hydrochloric acid or such a solution having 30 more or less separated chlorhydrin. This separated chlorhydrin however will be clearly soluble in water. If whitish drops which are not completely soluble in water form, olefin chlorids are being produced. 35 With a cell of the type shown, if the vapor space above the normal liquid level is 5 or 6 inches in the clear, the formation of olefin chlorids will not ordinarily occur, with proper regulation of the feed of gas and 40 steam. With proper operation of the cell the gases passing beyond the condenser will be nearly free of olefins (as indicated by analysis with the bromin absorption test). A slight amount should always remain to insure 45 presence of an excess over the chlorin in the reaction zone. They may be scrubbed with a little water to remove acid and used for supplying gas engines to furnish the power for the supply of electric current to 50 be used in carrying out the operation. In this type of cell I sometimes employ the supplemental cathode 17 placed directly above the anodes. This cathode tends to form, by well understood reactions, hypochlorites 55 which in the boiling solution are converted by the chlorin into chlorids and hypochlorous acid, $HClO$, which is freely volatile in water solutions at 97° C. and above and which likewise unites with the olefins to 60 form chlorhydrins. It may be that the ac-

tion of chlorin itself upon the olefins in the presence of ample amounts of water vapor to form chlorhydrins is due to a preliminary formation of hypochlorous acid. As to this however I express no opinion. With 70 the use of this supplemental cathode, both sides of the anodes are made operative and the capacity of the cell is considerably increased. Some fraction of the increased energy available however goes to form 75 chlorates.

The condenser used with this cell may be like that shown in Fig. 2 or may be any simple type of worm.

The temperature of 97°-100° C. indicated is that of the vapor space in operating at the ordinary atmospheric pressure. If a greater or less pressure is used, the temperature range will vary correspondingly. The temperature should be within two or three 85 degrees of that at which water will boil at the pressure used but below the boiling point of the brine used. It is not desirable to have the electrolyte actually boil if it is a saturated solution. 90

In the showing of Fig. 2 I illustrate a vertical type of cell wherein gas or a mixture of gas and steam is blown through the electrolyte instead of along its surface. If the electrolyte becomes dilute by reason of 95 condensation of steam, less steam is blown in with the gas. In this showing element 30 is a concrete housing or hydrogen and alkali chamber which may be made of concrete, brickwork or any other suitable material. It may be either cylindrical or rectangular in shape. At a point near the top it carries outlet 31 for hydrogen and at a point near the bottom outlet 32 for caustic soda. Inlet 33 allows introduction of steam 100 in this chamber. On the floor of this chamber is a slate or soapstone slab 34 on which the cell proper rests, making a liquid tight union at its base with the slab. The slab is in effect the floor of the cell proper. 105 Through the floor of the cell passes outlet 35 for brine. At the top is brine inlet 35'. The side walls of the cell as shown are composed of cathode 36 which may be of copper or iron; and may be made of wire gauze or 110 perforated or expanded metal. Within this cathode is diaphragm 37 which may be of porous concrete, asbestos, or any other suitable material. For the present purposes, since there is considerable agitation within 115 the cell which is apt to disintegrate asbestos in its ordinary form, if asbestos be used it is best first treated with a concentrated solution of water glass. Under the influence of the saturated brine of the electrolyte this 120 glass is precipitated within the pores of the asbestos as a stiff, mechanically strong colloid mass, which, while not interfering materially with electric conductivity or the 125 passage of the ions has nevertheless con- 130

siderable mechanical strength. Near this diaphragm are placed anodes 38 which may be of carbon or graphite. Inch rods spaced a quarter of an inch apart form a very good 5 anode for the present purpose. These rods pass through and are held by ring cover 39 which may be of slate or other acid resistant material. As shown, it rests on the top of the cathode and diaphragm, being 10 notched to receive their upper extremity and form a gas-tight union therewith. Any suitable lute may be used in this joint. Resting on this ring is hollow tile 40 of terra cotta or the like, forming a vapor dome 15 wherein reactions may be completed. This is closed by cover 41 through which passes gas introduction pipe 42 depending to the bottom of the cell where it carries lateral extensions 43 adapted to bubble gas up 20 along the anodes. Carried by the cover is a steam pipe 44 which may be of stoneware or of metal as may be desired. If made of metal, it may be copper or iron; but in such event it is connected to the source of energy 25 in such manner as to act also as a cathode. As shown this steam pipe is coiled into a spiral shape and lies as near the anodes as may be. The use of this heating pipe as a cathode considerably increases the output of 30 the cell as it enables both sides of the anodes to be active but it results in the formation of some chlorate. Also passing through the cover is vapor pipe 45 flanged at 46. By this flanged union it connects 35 through pipe 47 with a diagrammatically shown column still 48 of stoneware or any other acid resistant material. At the top this still carries thermometer 49 and vapor outlet 50. The vapor outlet is continued 40 through worm 51 in tub 52. Condensate from the worm is received in tub 53 having gas outlet 54. The condensate in this tub will divide itself into two layers, a lower one of oily chlorhydrins and chlorids which may 45 be withdrawn from time to time through outlet 55, and an upper layer of a saturated solution of chlorhydrins which may be returned to the still through pipe connection 56 for re-distillation.

50 The operation may be controlled in accordance with the appearance and odor of the condensate in 53. In normal operation no smell of chlorin should occur at this point. If olefin chlorids are forming the 55 condensate will have a chloroform like odor very different from and tending to overpower the chlorhydrin odor. The remedy is more steam and gas. Appearance of olefin chlorids is also indicated by whitish floating accumulations, sinking on stirring or 60 shaking. Chlorhydrins though also tending to float and sink on shaking, have a different look, forming clear floating drops, generally more or less yellow. The floating drops also tend to take a conoidal shape,

elongating downwardly centrally (something like a wasp nest) with the end of the cone breaking off and sinking from time to time.

In Figs. 3 and 4 I have shown another 70 type of vertical cell designed for compactness, capacity and economy of power. It is assembled by providing a longitudinal chamber or casing which may be of any convenient non-conductive material and as 75 shown is built up of hollow tiles 60 for the sake of heat-insulation, these tiles being laid in concrete wall 61. Within this casing may be as many unit cells, (as shown in Fig. 4), as may be desired. Each cell unit is provided with side walls 62 and bottom 63, of slate or other acid proof materials, these being simple inch or inch and a half strips. Within the narrow chamber thus formed are carbon anodes 64 passing upward 80 through cover 65 to current lead 66. Passing upward through the floor of the unit is brine outflow pipe 67, rising to the normal liquid level within the unit and leading outward past valve 68 to discharge in trough 90 69, leading to a resaturator (not shown). This pipe and trough are of non-conductive material. Brine is supplied from main 70 to funnel 71 on pipe 72. This pipe extends within the unit at 73 and has a drain connection 74. Gas is supplied at 75, and passes through a glass sight-feed device 76. Steam is introduced with it by means of connection 77. Beneath the anodes is a perforated gas distribution pipe 78 of glass or terra cotta. 100 Near the top of the unit vapor discharge 79, which may be a glass tube, leads outward, being given a slight angle to permit reflux of any condensate. This discharge communicates with vapor trunk 80, leading to a 105 condenser (not shown). As many as may be desired of these units are assembled together as more fully shown in Fig. 4. As there shown, the unit is composed of two diaphragm walls, 81. Beyond these dia- 110 phragms are cathodes 82 which may be of any of the usual materials. As shown, however, they are composed of a porous or open textured mass of copper oxid having embedded copper wire or gauze 83, for the 115 sake of conductivity. The unit being intended for use in series, the two cathodes, *a—a* of unit A are connected through 84 with the anode of unit B. There being a potential drop between the two cathodes *a* and 120 *b* of units A and B, the chamber between them is divided into two parts, C and D, or subchambers, by partition 85 of slate or the like. On each side of this partition is an alkali outlet, 86, a steam and air inlet 87 and 125 a steam or hydrogen outlet 88.

In the use of this structure, the operation, so far as the chlorhydrin making operation is concerned, is much the same as that in Fig. 2. The steam and gas pass up around 130

- the anodes from 78 and form chlorhydrin vapors which are led away through 79 to 80; the latter serving both as a vapor trunk and as a reaction chamber. Cathodes 82 however 5 ever operate in a novel manner. Air being introduced with steam at 87 and the whole apparatus being at about 100° C., the copper oxid of the cathodes acts as a regenerated depolarizer, the reduced copper being oxidized by the air. It is best to free this air of CO₂ by washing with air or a little caustic soda.
- If no air be introduced, the cathodes operate in the usual manner; and in this event 15 they may be of iron or any other suitable material. For depolarization while other bodies may be used, such as manganese oxids, I regard the copper oxid as well adapted.
- 20 In Fig. 5 I have shown a cell intended for the recovery of the chlorin converted into hydrogen chlorid in the reaction. This cell which has no diaphragm is composed of a casing 100 of wire netting or expanded 25 metal, lined with slate 101 held in place by the gripping action of fine concrete plastering 102. Suitably supported below normal liquid level 103 are anode 104 and cathode 105. The latter is intended to serve also as 30 a heating member and may be composed of copper or lead tubing and be connected to steam conduit 106. Drain 107 is provided for cleaning out. Chlorin is introduced at 108 and gas or vapor at 109. Steam may be introduced with the gas by 110. Vapors are 35 led off to a condenser by vertical conduit 111 which may be of any suitable size or material and may lead to an auxiliary reaction chamber.
- 40 In the operation of this structure chlorin from another source is introduced at 108 and reacts with gas from 109. The hydrochloric acid produced in the reaction condenses with the aqueous vapors of the chamber and joins the liquid layer while chlorhydrin vapors pass outward through 111. The heater cathode 105 keeps the liquid at 45 or near the boiling point to furnish the aqueous vapor needed in the reaction while 50 cathode and anode coöperate to reconvert the hydrochloric acid into chlorin and keep the hydrochloric acid concentration of the liquid at a low point; which is desirable. The level of aqueous liquid is kept constant 55 or nearly so, the reflux action of 111 returning nearly all the vapor passing forward with the chlorhydrin. Steam from 110 is used mainly to replenish losses of water.
- 60 While I have described the use of oil gas, it is obvious that the described method may be equally well applied to the individual olefins which it contains. For example ethylene, made by hydrogenation of acetylene 65 or by dehydrating alcohol, may be so treated.

Other olefin rich gas, such as that from coking coal, charring wood, etc., may be employed. The richest oil gas is that made by passing heavy oils, such as gas oil, through a hot retort at say 700° C. It should not be "fixed" by reheating to a high temperature. Gases from "cracking stills" in petroleum refineries may be used in lieu of specially made gas.

Instead of using gaseous olefins, (those normally gaseous at say 20° C.), the volatile liquid olefins contained in unrefined cracked gasolenes may be employed. The operation is exactly the same as hereinbefore described save that gasolene vapors are used in lieu of oil gas.

By lowering the cell temperatures somewhat or by restricting the amount of water vapor in the reaction zone, olefin chlorids may be produced in lieu of chlorhydrins. 85 They distil over at somewhat lower temperatures. For some purposes simultaneous production of both chlorids and chlorhydrins is desirable; as in producing mixed solvents containing both.

90 Bromhydrins may be produced in the same manner as chlorhydrins by substituting a bromid, such as sodium bromid, for the chlorid in the electrolytic cell.

95 As stated, chlorhydrins may be made without electrolysis by mingling gaseous chlorin from any suitable source with steam and olefins in a suitable reaction chamber (application No. 34678). This results in the production of vapors of chlorhydrins and of 100 hydrogen chlorid (HCl or hydrochloric acid), as in the present invention. In the present invention, this hydrochloric acid is reëlectrolyzed to form more chlorin. The two inventions may be usefully combined, chlorin from another source being blown into any of the cells shown through inlet 90 by means of steam from 91. With 105 introduction of supplemental chlorin, in addition to that which is generated in the cell, the chlorhydrin output of the cell can of course be considerably increased; but this is at the expense of the alkali production. If sufficient supplemental chlorin be so introduced, the function of the cell may be (as 110 shown more specifically in Fig. 5) simply the electrolysis of the hydrogen chlorid produced in the chlorhydrin formation; and in this event no sodium or potassium chlorid is used in the electrolyte. Ordinarily however in such a combination operation I use 115 some sodium chlorid.

120 The hydrochloric acid formed in the operation need not be returned to the cell for reëlectrolysis, although this is usually done 125 in the present embodiment of my invention, but may be removed for use elsewhere. In the apparatus of Fig. 2 for example a solution of HCl may be removed at valved drain 200. In Fig. 3, trunk 80 may be inclined 130

to send condensed acid liquid to collecting means not shown. In any of the figures an increase in the amount of steam used or vapors generated will send HCl in greater 5 or less amount beyond the cell.

The HCl solution may be used for chemical generation of chlorin for making chlorhydrins; or may be used for replenishing the chlorin where chlorhydrins are made with 10 the aid of reducible, autoxidizable chlorids such as CuCl₂, FeCl₃, etc.

What I claim is:

1. The process of preparing solvent bodies which comprises electrolyzing a hot aqueous 15 chlorid solution in a suitable electrolytic cell having an anode and during electrolysis supplying an olefin into the vicinity of the anode while removing vapors of produced chlorinated products.

2. The process of preparing solvent bodies which comprises electrolyzing a hot aqueous chlorid solution in a suitable electrolytic cell having an anode and during electrolysis supplying a gaseous olefin into the vicinity of 20 the anode while removing vapors of produced chlorinated products.

3. The process of preparing solvent bodies which comprises electrolyzing a hot aqueous chlorid solution in a suitable electrolytic cell 30 having an anode and during electrolysis supplying oil gas into the vicinity of the anode while removing vapors of produced chlorinated products.

4. The process of preparing chlorhydrins 35 which comprises electrolyzing a hot aqueous solution of a chlorid in a suitable cell having an anode and during the electrolysis supplying an olefin into the vicinity of the anode under conditions permitting presence 40 of an ample amount of water vapor to dilute such olefin during its reaction with chlorin evolved at the anode.

5. The process of preparing chlorhydrins 45 which comprises electrolyzing a hot aqueous solution of a chlorid in a suitable cell having an anode and during the electrolysis supplying a gaseous olefin into the vicinity of the anode under conditions permitting presence 50 of an ample amount of water vapor to dilute such olefin during its reaction with chlorin evolved at the anode.

6. The process of preparing chlorhydrins 55 which comprises electrolyzing a hot aqueous solution of a chlorid in a suitable cell having an anode and during the electrolysis supplying oil into the vicinity of the anode under conditions permitting presence of an ample amount of water vapor to dilute such oil gas during its reaction with chlorin 60 evolved at the anode.

7. The process of making solvents which 65 comprises electrolyzing a chlorid solution in a suitable cell at a temperature around 100° C., removing and recovering the alkali produced and during electrolysis supplying an

olefin to such cell at a rate sufficiently rapid to combine with the chlorin as fast as produced by electrolysis and removing vapors of chlorinated products as fast as formed.

8. The process of making solvents which 70 comprises electrolyzing a chlorid solution in a suitable cell at a temperature around 100° C., removing and recovering the alkali produced and during electrolysis supplying a gaseous olefin to such cell at a rate sufficiently rapid to combine with the chlorin as fast as produced by electrolysis and removing vapors of chlorinated products as fast as formed.

9. The process of making solvents which 80 comprises electrolyzing a chlorid solution in a suitable cell at a temperature around 100° C., removing and recovering the alkali produced and during electrolysis supplying oil gas to such cell at a rate sufficiently rapid 85 to combine with the chlorin as fast as produced by electrolysis and removing vapors of chlorinated products as fast as formed.

10. In the manufacture of solvents, the process which comprises electrolyzing a 90 chlorid solution in a diaphragm cell having an anode chamber and during electrolysis continuously introducing an olefin and steam into such anode chamber while continuously removing vapors of products formed from 95 such olefin.

11. In the manufacture of solvents, the process which comprises electrolyzing a 100 chlorid solution in a diaphragm cell having an anode chamber and during electrolysis continuously introducing oil gas and steam into such anode chamber while continuously removing vapors of products formed from the olefins of such oil gas.

12. In the manufacture of solvents, the 105 process which comprises electrolyzing a hot aqueous solution of a chlorid in a suitable chamber, during electrolysis introducing an olefin into such chamber in proximity to the anode, removing aqueous vapors and vapors 110 of chlorinated products formed, cooling the removed vapors somewhat to condense and return an aqueous condensate and further cooling the vapors to condense and collect the chlorinated products.

13. In the manufacture of solvents, the process which comprises electrolyzing a hot aqueous solution of a chlorid in a suitable chamber, during electrolysis introducing oil gas into such chamber in proximity to the anode, removing aqueous vapors and vapors 120 of chlorinated products formed, cooling the removed vapors somewhat to condense and return an aqueous condensate and further cooling the vapors to condense and collect 125 the chlorinated products.

14. The combination, with an electrolytic cell arranged for the electrolysis of chlorids, and means for heating such cell, of means including a source of olefinic gases for com- 130

mingling said gases and the chlorin evolved by the cell, and means for condensing and removing the products of reaction of the chlorin and olefinic gases.

5 15. In an electrolytic apparatus, a cell adapted for the electrolysis of chlorids, means for feeding steam into such cell, means for feeding olefinic gases or vapors into such cell and means for removing vapors therefrom, such means including means for refluxing and returning aqueous portions of such vapors.

16. In an electrolytic apparatus, a cell adapted for the electrolysis of chlorids, 15 means for feeding steam into such cell, means for feeding olefinic gases or vapors into the anode chamber of such cell and means for removing vapors therefrom.

17. In an electrolytic apparatus, a cell 20 adapted for the electrolysis of chlorids, means for feeding steam into such cell, means for feeding olefinic gases or vapors into such cell and means for removing and condensing vapors therefrom, such means 25 including means for refluxing and returning aqueous portions of such vapors.

18. In an electrolytic apparatus, a cell

having a diaphragm and adapted for the electrolysis of chlorids, means for introducing olefinic gases into the anode chamber of such cell, means for heating such anode chamber and means for removing and condensing vapors from such anode chamber.

19. The process which consists in simultaneously heating and electrolyzing an aqueous solution of a halogen compound to drive off the halogen in gaseous form, commingling an unsaturated hydrocarbon in gaseous state with said halogen in gaseous form and water vapor, leading off the the resultant 40 vapors and recovering the halogenated products therefrom.

20. The process which consists in simultaneously heating and electrolyzing an aqueous solution of a halogen compound to drive 45 off a mixture of halogen and water in gaseous and vapor form, commingling an unsaturated hydrocarbon in gaseous state with said mixture of water vapor and halogen, leading off the resultant vapors and recovering the halogenated products therefrom.

In testimony whereof, I affix my signature.

K. P. McELROY.
